UNITED STATES PATENT OFFICE.

EARL E. McCOLLUM, OF DOWNTERS GROVE, ILLINOIS.

INTERNAL-COMBUSTION ENGINE.

1,290,263.

Specification of Letters Patent.

Patented Jan. 7, 1919.

Application filed August 25, 1916. Serial No. 116,769.

To all whom it may concern:

Be it known that I, EARL E. McCOLLUM, a citizen of the United States, residing at Downers Grove, in the county of DuPage 5 and State of Illinois, have invented certain new and useful Improvements in Internal-Combustion Engines, of which the following is a specification.

This invention relates to improvements in 10 internal combustion engines.

One of the objects of my invention is to provide in combination with a rotary valve, a valve driving mechanism by means of which the valve will be so actuated as to give 15 rapid opening and closing of the ports with a substantial dwell between opening and closing, thus affording a free passage-way for rapid movement of the gases, and permitting accurate timing of the valve 20 functions.

A still further object of my invention is to provide a valve driving mechanism which can be readily mounted in the crank case of a gas engine, occupying a minimum amount 25 of space and that will be efficient and dependable in its operation.

Still other and further objects will become apparent to those skilled in the art, from a consideration of the following description 30 and drawing wherein:

Figure 1 is a plan view of my improved engine and valve, with the valve cover removed.

Fig. 2 is a vertical transverse sectional 5 view on the line 2-2 of Fig. 1.

Fig. 3 is a vertical sectional view on the line 3-3 of Fig. 1 showing the valve detached and on a reduced scale.

Fig. 4 is a horizontal sectional view on 10 line 4-4 of Fig. 2.

Fig. 5 is a vertical sectional view on line 5-5 of Fig. 4 showing the crank-shaft and valve driving rod in elevation.

Fig. 6 is a vertical sectional view on line 6-6 of Fig. 4, showing the crank-shaft and valve driving rod in elevation, and:

Fig. 7 is a fragmentary sectional view on line 7-7 of Fig. 6.

For the purpose of fully disclosing my valve driving mechanism I have illustrated the same in connection with a valve and engine forming the subject matter of my co-pending application, Serial No. 142,334, entitled "Improvements in gas engines," filed by me January 15th, 1917, the same forming a division of this application.

In general the engine comprises a crank-case A with bottom closure wall B and a top closure wall C, upon which are cast the four cylinders—D, E, F and G. The cylinders 60 are divided into two pairs—D and E, extending upwardly and outwardly at an angle from one side of a vertical plane passed through the crank-shaft and F and G projecting from the other side. The included 65 angle made within the two pairs of cylinders is approximately 30 degrees, so that each cylinder is inclined 15 degrees to the vertical. The two sets are positioned in staggered relation so as to locate them all as near 70 as possible to a central rotary valve H. By means of this peculiar location of the cylinders it is possible to bring them all into close relationship to the valve H, which is so designed as to serve as inlet and exhaust 75 controlling valve for each of the four cylinders.

The valve itself as indicated in general at H is positioned approximately centrally with respect to the crank-casing, and is so arranged that four ducts, D¹, E¹, F¹ and G¹ 80 connect the four cylinders with the valve casing each duct serving as both inlet and exhaust passages.

A preferred form of rotary valve is illustrated in Figs. 1, 2 and 3 with an annular 85 casing 10 provided with a cooling water passage 11 to which suitable connection may be made. The upper lid or cap of the casing comprises a dome-shaped chamber 12 having an annular flange 13 for co-action with the 90 upper flange on the annular casing 10 to which it is secured. This upper dome-shaped cover 12 serves as a passageway for the exhaust gases which are taken away through the flanged head 14. The lower end 95 of the casing is covered by similar chambered cap 15 with annular flange 16 for attachment to the flange at the lower end of the annular valve casing. This chamber serves as an inlet duct for the combustible 100 mixture which is taken into the casing through the flanged opening 17, to which the carburetor is attached.

The valve itself comprises a tapered drum 18 having two ports 19 and 20, opening to its 105 periphery, the one extending upwardly as in 21, to serve as an exhaust port, and the other extending downwardly as at 22, to serve as an inlet port. The valve H rotating within its annular casing 10 has its downwardly extending inlet port 22, at all times opening to the intake duct 15, whereas its upwardly ex-

tending exhaust port 21 at all times communicates with the upper cap or exhaust duct 12. The inlet and exhaust ports are positioned approximately 90 degrees apart 5 around the periphery of the valve, and the valve traveling in a clockwise direction, looking at Fig. 1, obviously serves the cylinders in the following order—D, F, G and E, or to give their numerical order from the 10 front, 1, 2, 4 and 3.

The valve is rotated by a substantially vertically extending shaft 23, which projects upwardly through the crank-case cover C, its lower end extending downward to its 15 driving mechanism, and its upper end projecting through the lower wall of the intake passage, and fastened within the centrally positioned tubular hub. The shaft 23 may be hollow to carry oil from the crank-case 20 to the rubbing surfaces of the valve, suitable ducts being provided within the valve for its distribution and a pump of any suitable type may be connected to the lower end of the shaft. The valve is substantially hollow to 25 provide a cooling water passage, its upper end having a hollow dome 25, communicating with a vertically extending axially positioned pipe 26, through which the cooling water is carried away from the valve. The 30 lower end of the valve extends downwardly in the form of a hub 27, which is drilled out, providing a plurality of water channels 28, which communicate at their lower ends with the interior of a bored out casting 29, into 35 which leads a cooling water-carrying pipe 30. The lower end of the casting 29 is provided with a packing 31, which is held in position on the rotating shaft 23 by means of a collar 32, secured to the shaft by means 40 of a set screw. The upper end of the casting 29 is also provided with a water-tight packing 33, the packing nut of which is threaded upon the downwardly extending nipple 34 of the inlet passage 15. The 45 upwardly extending pipe 26 projects through a nipple 35, formed on the upper wall of the exhaust passage 12, and connects at its upper end with a cap 36 with which it makes water-tight connection through the medium of a packing 37. A discharge pipe 38 leads 50 into the cap 36 and carries off the cooling water from the valve, and returns it to the circulating system.

Proper rotation of the valve is obtained 55 by means of a valve-driving gearing, operating upon the same principle as that illustrated and described in my co-pending application, Serial No. 19,285, filed April 5, 1915, and entitled "Valve gearing mechanism". In this earlier filed application, 60 above referred to, mechanism is shown for driving a rotary valve with a movement of the valve at a rate approximately proportional to the co-sine of the crank angle. By 65 this means I am enabled to drive my rotary

valve so that the ports are quickly opened and closed, the valve slowing up between the opening and closing movements, so as to permit a substantial dwell to permit the gases to have free course through the passageways. 70

In the present application I have shown a somewhat different mechanism for accomplishing this same valve movement, this mechanism being designed more particularly for insertion in the crank-case of a multi-cylinder gas engine provided with a vertically disposed valve-driving spindle. Extending axially through the crank-case A is a crank-shaft I having properly positioned cranks D², F², E², G². Intermediate the 80 cranks E² and F² there is provided an eccentric portion 50 through the medium of which the valve mechanism is driven. With the cranks E², F² in the position indicated in dotted lines in Fig. 2 the eccentric 50 is positioned vertically above the center of the shaft, a line passing through the center of the eccentric and the center of the shaft being parallel with the valve-driving spindle 23 which of necessity is angled slightly to 90 the vertical so that its lower end may pass to one side of the crank-shaft.

The eccentric is surrounded by a split bearing 51 held in a cage 52 by a removable cap 53, the cage having horizontally extending pins on the ends of which are vertically disposed slides 55, reciprocable within the vertical guideways 56. The guideways 56 are formed in a pair of upstanding arms 57 which in turn are provided with horizontal 100 grooves 58 for sliding engagement with the horizontal guides 59 bolted to each side of the crank-case. The guides 59 project inwardly at the top and bottom of the blocks 60 which are secured by means of bolts 61 105 against the inner faces of inwardly projecting lugs 62 which may be integral with the inner wall of the crank-case. The horizontally reciprocable upstanding arms 57 are rigidly joined beneath the crank-shaft by means 110 of a plate 63 provided with a slot 64 through which projects the valve-driving spindle 23. On the lower end of the spindle 23 is secured a pinion 65 lying in the horizontal plane of the opposed racks 66, 67, spaced apart for a 115 distance slightly greater than the diameter of the pinion and formed in the opposite walls of an oval aperture cut in plate 68. The transverse ends of the plate 68 are provided with slides 69 for engagement with the 120 guiding grooves 70 formed on the downwardly extending wings 71 of the plate 63 carried by the upstanding arms 57.

At the transverse ends of the rack plate 68 are secured a pair of rollers 72 which engage in the slots 73 formed in the arms 74 projecting downwardly from the cage 52 in which the eccentric is journaled. These forwardly and downwardly extending arms 74 are provided with slots having upper and 130

lower offset end portions joined by a central diagonal portion, as illustrated in Fig. 5, so that the vertical reciprocation of the arms cause movement of the rack plate axially with respect to the crank-shaft for engagement of first one and then the other of the racks 66 and 67 with the pinion.

From the above it will be evident that the eccentric in making its complete revolution will cause the cage 52 to travel both vertically and horizontally in a transverse plane, the horizontal and vertical components of movement being transformed into transverse and axial movement of the rack plate 68. The vertical component of eccentric movement shifts the rack from one side to the other, causing the pinion to engage first with rack 66 and then with rack 67. The horizontal component of eccentric movement displaces the rack transversely, consequently driving the pinion and its valve actuating spindle 23.

By reference to Fig. 7 the movement of the valve spindle may be more easily explained. The plate 68 has a right and left movement with an up and down movement intermediate each change of side movement. Thus referring to Fig. 1 if the shaft is rotating in a counter clockwise direction the eccentric moves to the left and downwardly. The movement of the eccentric to the left slides the rack to the left rotating the valve spindle in a counter clockwise direction (looking at Fig. 7). The downward component of eccentric movement has no effect upon the rack plate until the angled portion of slot 73 (see Fig. 5) displaces the rack plate upwardly shifting the rack 67 into engagement with the pinion. The eccentric then moves rack plate 68 to the right continuing rotation of the valve spindle in the same direction. The same action is repeated as the rack 67 is moved to the extreme left of its travel, and the upper rack 66 is then shifted down into engagement with the pinion. As the horizontal component of eccentric movement is utilized in the rotary movement of the valve spindle pinion it is evident that this movement will be substantially proportional to the co-sine of its angular movement, permitting a rapid opening and closing of the valve port with an intermediate dwell while the port is open.

By means of this movement I am able to secure a quick opening and closing of both inlet and exhaust ports with a substantial dwell between the opening and closing movement permitting free passage of the gases.

The valve mechanism may be readily removed from the crank casing bodily by removing the bolts 61 and the crank case bottom D.

Whereas I have illustrated and described a single embodiment of my invention it will be obvious that various changes and modi-

fications may be made therein without departing from the spirit and the scope of the following claims.

Having described my invention, what I claim is:

1. The combination with the shaft, cylinder and rotary valve of an internal combustion engine; of a valve driving mechanism comprising a crank rotated by said shaft, a valve driving shaft, a pinion for driving the valve shaft, a pair of gears arranged for alternative driving engagement with the pinion, means for transmitting the component of crank movement at substantially right angles to the cylinder axis into rotary movement of the pinion by one or the other of the gears, and means for transmitting the component of crank movement substantially parallel with the cylinder axis into shifting said gears into and out of engagement with the pinion. 70

2. The combination with the shaft, cylinder and rotary valve, of an internal combustion engine; of a valve driving mechanism comprising a crank rotated by said shaft, a valve driving shaft, a pinion for driving the valve shaft, a pair of gears lying in the same plane as the pinion and relatively movable with respect thereto for alternative engagement therewith, means for transmitting the component of crank movement at substantially right angles to the cylinder axis into rotary movement of the pinion by one or the other of the gears, and means for transmitting the component of crank movement substantially parallel with the cylinder axis into shifting said gears into and out of engagement with the pinion. 90

3. The combination with the shaft, cylinder and rotary valve, of an internal combustion engine; of a valve driving mechanism comprising a crank rotated by such shaft, a valve driving shaft, a pinion for driving the valve shaft, a member having an opening therein to receive the pinion, gear teeth 110 formed on opposite sides of said opening for alternative driving engagement with the pinion, means for transmitting the component of crank movement at substantially right angles to the cylinder axis into lengthwise movement of said member to cause driving engagement between the gear teeth and pinion, and means for transmitting the component of crank movement substantially parallel with the cylinder axis into transverse movement of the member to shift either one or the other of said sets of gear teeth into and out of engagement with the pinion. 115

4. The combination with the shaft, cylinder and rotary valve of an internal combustion engine; of a valve driving mechanism comprising a crank rotated by said shaft, a substantially vertical valve driving shaft, a pinion carried by the lower end of said shaft, a member having an elongated slot therein 130

of a width greater than the diameter of the pinion, gear teeth formed on opposite sides of said slot for alternative driving engagement with the pinion, means for transmitting the component of crank movement at substantially right angles to the cylinder axis into longitudinal movement of said member, and means for transmitting the component of crank movement substantially parallel to the cylinder axis into transverse movement at right angles to the longitudinal movement of said member thereby shifting either one or the other of said sets of gear teeth into or out of engagement with the pinion.

5. The combination with the shaft, cylinder and rotary valve of an internal combustion engine; of a valve driving mechanism comprising a crank rotated by said shaft, a valve driving shaft, a pinion for driving the valve shaft, a pair of gears arranged for alternative driving engagement with the pinion, a carriage reciprocable on lines at substantially right angles to the cylinder axis and driven by the crank, a connection between said carriage and gears for causing rotation of the valve driving pinion, a second carriage driven by the crank and reciprocable at right angles to the reciprocatory movement of the aforesaid carriage, and connections between the last mentioned carriage and the gears for alternatively shifting them into and out of engagement with the pinion.

6. The combination with the crank case of an internal combustion engine, of a crank shaft extending therethrough, a rotary valve driving shaft projecting thereinto, a crank carried by said shaft, horizontal guide-ways carried by the opposite sides of the crank case, a carriage horizontally reciprocable on said guide-ways, vertical guide-ways in said carriage and a second carriage vertically reciprocable within said last mentioned guide-

ways, a bearing in the last mentioned carriage for the said crank, a pinion carried by the lower end of said valve driving shaft, a plate positioned in the same plane as the pinion and having an elongated opening therein to receive the pinion, the width of the opening being greater than the diameter of the pinion, gear teeth formed on opposite sides of said opening for alternative engagement with the pinion, a connection between the first mentioned carriage and said plate for reciprocating the same longitudinally, and a connection between the last mentioned carriage and the plate for shifting the same transversely to alternatively engage the said sets of gear teeth with the pinion.

7. The combination with an engine shaft, cylinder and rotary valve of an internal combustion engine; of a valve driving mechanism comprising a valve driving shaft, an eccentric rotated by said engine shaft, rectangularly movable means for rotating said valve shaft at an intermittent rate, and means driven by said eccentric for actuating said rectangularly movable means.

8. The combination with an engine shaft, cylinder and rotary valve of an internal combustion engine; of a valve driving mechanism comprising a valve driving shaft, an eccentric driven by said engine shaft, rectangularly bodily movable means for intermittently rotating the valve shaft in a single direction, and means driven by said eccentric for driving said rectangularly bodily movable means.

In testimony whereof I hereunto set my hand in the presence of two subscribing witnesses.

EARL E. MCCOLLUM.
